MASK FOR EXCLUDING AMBIENT SOUNDS

Horace L. Webb, San Francisco, Calif., assignor
to Dictavox Company, Inc., Washington, D. C.,
a corporation of Delaware.

Application May 7, 1946, Serial No. 667,827

4 Claims. (Cl. 179—183)

1

This invention relates to a dictating mask.

The primary object of the invention is to provide a mask to cover the mouth, nose and part of the face of a person dictating into a device for the purpose of recording, in such a manner that the voice of the person dictating is not heard by others. The principal purpose of this dictating mask is to allow direct dictation into recording machines instead of stenographic or the like notes which latter thereafter must be dictated in such machines for the purpose of transcribing the same. The invention has a variety of uses, for instance it may be used by court reporters, or reporters at hearings or other occasions, wherein in testimony or other discussion at conferences or the like can be immediately dictated by the one taking the report without disturbing the participants in the discussion or hearing. The direct taking of such notes onto a record making apparatus of any suitable type, facilitates transcribing and expedites the obtaining of transcripts of hearings and the like.

The features of this invention include a mask which covers the nose and mouth yet permits the breathing of outside air by the person dictating without allowing sound to escape to the outside of the mask except to the recording apparatus through a microphone or transmitter device in the mask; another feature is an absorbent lining inside the mask which may be interchangeable so that if the mask is used by different persons they, after each use, can replace the lining, said absorbent lining or pad absorbs moisture caused either by perspiration or other condensation from the mouth, nose or pores of the person using it; another feature is the flexible and easy connection of the microphone or transmitter held at the point of the mask in such a way that the head of the operator can be turned in various directions to watch the lips or faces of the persons whose testimony or statements have to be transcribed or reported, and also to watch all events at the hearing and obtain a more complete and full report than it is possible in case of stenographic notes or the like; another feature of the invention is the provision of a suitable mask which can be easily held on the face of the operator by a handle or by a strap or the like without inconvenience and provide a soundproof dictating chamber on the face, yet allow unobstructed breathing and facilitate direct recording by sound transcription, and which excludes exterior sounds from the mask and the microphone.

Another object of this invention is to provide a dictating mask which is highly useful and simple in construction. Convenience of arrangement, lightness and comparative inexpensive of manufacture are further objects which have been borne in mind in the production and development of the invention.

The essential features of the invention involved

2

in the carrying out of the objects indicated are susceptible to modification, but a preferred embodiment of the invention is shown in the accompanying drawings, in which:

5 Fig. 1 is a perspective view of the dictating mask constructed in accordance with my invention, showing the same in position on the face of an operator;

Fig. 2 is a sectional view of the mask;

10 Fig. 3 is a cross-sectional view of the mask, the section being taken on lines 3—3 of Fig. 2;

Fig. 4 is a sectional detail view showing the mounting of the microphone on the mask;

15 Fig. 5 is a perspective view of the transmitter or microphone in a mask showing the detachable connection of the transmitter wire or line to said microphone; and,

Fig. 6 is a perspective view of a slightly modified form of my mask.

20 20 In carrying out my invention I make use of a mask 1 which is preferably of a frusto-conical shape, the mouth piece or end 2 of which is sufficiently large to cover such portion of the face as necessary to confine the sound of dictation to

25 the microphone within the mask and to exclude exterior sounds from the mask and the mike. The illustrative form of the mask 1 herein fits over the nose, face and chin of the wearer or operator, as indicated in Fig. 1. The mask body is preferably made of flexible material such as rubber or fabric or the like. The narrower or smaller end of the mask 1 is formed into a retaining flange 3 which is made with an elastic bead or the like

30 for the purpose of gripping the rim 4 of a microphone 6 of the electronic transmitter type. A strap 7 is the illustrative form for holding the mask in place. This strap 7 is suitably secured in loops 8 on the large end or mouth piece 2 of the mask 1, and is adapted to be placed around the head and tightened for holding the mouth piece 2 of the mask 1 tightly against the contour of the face of the operator. A handle 5 extends

35 40 from the lower side of the mask 1, so that the mask may be held in place by hand in the event a strap is undesirable.

45 The mask has a plurality of vents 9 on the upper portion on the opposite sides so that the said vents 9 are located on the opposite sides of the nose of the wearer. The vents extend from the edge of the larger end 2 of the mask 1 to a limited extent inwardly and taper away at a point spaced from the face to allow the entry of air to facilitate breathing of the operator.

50 55 Inside of the mask 1 is inserted an absorbent lining 11. This absorbent lining 11 is made in the form of a frusto-conical lining conforming to the inner periphery or surface of said mask 1 and extends from the larger mouth 2 to and

60 60 around the periphery of the rim 4 of the microphone 6, and over partly to the outside face of

the microphone 6 so as to prevent loss or escape of sound thereat. The absorbent lining 11 in this form is made with dents or passages 12 spaced apart in the same manner as the vents 9 on the mask 1 so as to fit into the same and allow the passage of air therethrough. The additional function of the vents 9 in the mask 1 is the location and holding of the absorbent lining 11 in place. As the absorbent lining 11 extends to the larger end or mouth piece 2 of the mask 1 it lines the area which engages the face of the operator and thereby it prevents undue and unnecessary rubbing of the face by the mask material, and also absorbs perspiration or other moisture that may issue from the face of the user.

The microphone 6 is snapped in place as heretofore described to be held by the bead 3 at the smaller end of the mask 1. It is preferable that the microphone be provided with a socket indicated at 13 in Fig. 5 so that the mask may be handled as a separate unit and after in place on the face, a line 14 from the recording machine may be plugged into said socket 13 by a suitable plug 16.

In operation the operator fits the mask in place on the face in front of the nose and mouth as shown in Fig. 1 and holds the mask by the handle 5 or tightens the strap to hold the mask in position. Then the electrical connection to a suitable recording machine is completed by plugging the plug 16 into the socket 13 of the microphone 6. Thereafter the operator can easily view the entire hearing room and watch the proceedings and record all proceedings, testimony and conversations in the mask which is transmitted through the microphone and the electrical conductor line 14 to a suitable electrical or electronic recording machine, not shown. After each use the operator may change the absorbent lining 11 to a fresh lining, or if the reporters are changed during the hearing each may change the absorbent lining when he takes over the recording mask, or carry his own mask, as the need may arise. The absorbent pad muffles the sound so that the voice of the operator, as he dictates to report the proceedings, is taken by the microphone and is concentrated to the microphone without the sound escaping into the hearing room and in any way interfering with or disturbing the proceedings. The device is simple, is easy to handle, it does not require any adjustment and it greatly facilitates the direct oral reporting and recording of proceedings of the type where heretofore various stenographic or stenotype devices were utilized, and it entirely obviates the necessity for redictating reports taken at a hearing.

I claim:

1. In a dictating mask structure, a hollow mask body of self-supporting material, said body having first and second ends, said first end being an open face engaging portion to fit over the mouth and nose of the operator while the body is manually held, an electrical microphone mounted within said body at said second end having a flexible conductor for attachment to a dictating machine, an absorbent pad lining the inside of said mask body and extending to said first end to engage the face, and a breather passage in the form of a groove in the inner surface of the body and open at said first end constituting the sole communication between the interior of the mask and the atmosphere, said absorbent pad interfitting into said groove.

2. In a dictating mask structure, a hollow mask body of self-supporting material, said body being frusto-conical to thereby provide relatively larger and smaller open ends, the larger end functioning to marginally contact the face of the dictator, said mask body having inwardly extending vent passage means in its inner surface open to the atmosphere at the margin of said larger end, said body adjacent said smaller end being elastic and provided with an internal annular groove, an electrical microphone removably located in said body having means in said groove form fitted by the elastic material whereby the latter snaps over the last-mentioned means, flexible conductor means for attachment to a recording machine, said flexible conductor means being in separable relation to the microphone and removably applicable to said microphone at said open smaller end of the body.

3. In a dictating mask structure, a hollow mask body of self-supporting material having an open end portion to marginally contact the face of the dictator, an electrical microphone, contacting means on the body and microphone in spaced relation to said open end detachably supporting said microphone, and an absorbent lining form-fitting the interior of the mask body having a portion extending between said means on said body and microphone, said portion including means whereby the lining is removably held in place.

4. Dictating apparatus comprising a dictating machine, a hollow dictating mask body having first and second ends, said first end being an open face engaging portion to fit over the mouth and nose of the operator, an electrical microphone within said dictating mask body at said second end, a flexible conductor, said flexible conductor being connected to said dictating machine and said microphone, said mask body being of self-supporting material, said mask body at the second-mentioned end being made of elastic material whereby it snaps into engagement over said microphone, said mask body having a breather groove in its inner surface and open at said first end constituting the sole communication between the interior of the mask and the atmosphere, and an absorbent lining form-fitting the interior of the mask body having a portion extending between the same and said microphone whereby the lining is removably held in place, said lining extending to said first end.
